DESIGN FOR A SPECTACLE FRAME

José A. Martinez, Habana, Cuba

Application September 21, 1934, Serial No. 53,342
In Cuba May 22, 1934

Term of patent 3½ years

To all whom it may concern:

Be it known that I, José A. Martinez, a citizen of the Republic of Spain and resident of Habana, Cuba, whose post-office address is Neptuno Street No. 180, Habana, Cuba, have invented a new, original, and ornamental Design for a Spectacle Frame, of which the following is a specification, reference being had to the accompanying drawing, forming part thereof.

Figure 1 is a front elevation of a spectacle frame showing my new design, while Fig. 2 is a plan view thereof.

I claim:

The ornamental design for a spectacle frame, substantially as shown.

JOSÉ A. MARTINEZ.
